FLOOR COVERING IMPLEMENT

Irvin C. Reed, Mishawaka, Ind.

Application September 6, 1939, Serial No. 293,652

1 Claim. (Cl. 254—124)

The present invention relates to new and useful improvements in implements or tools adapted for use by floor covering craftsmen.

The principal object of the present invention is to provide an implement of the leverage throw type constructed and arranged for urging tiles and other floor and wall facing elements into proper position.

Another important object of the invention is to provide an implement which is capable of convenient operation and which when used will expedite work with more efficient results.

Another important object of the invention is to provide an implement which in use can accommodate foot pressure of the craftsman when the implement is being employed to properly move a tile or other building element into definite position and permit holding of the element until it has substantially adhered in place.

These and various other important objects and advantages of the invention will become apparent to the reader of the following specification.

In the drawings:

Figure 1 represents a side elevational view.

Figure 2 is a top plan view.

Figure 3 is a front elevational view.

Figure 4 is a section on the line 4—4 of Figure 1.

Figure 5 is a vertical sectional view taken substantially on the line 5—5 of Figure 1.

Referring to the drawings wherein like numerals designate like parts, it can be seen that one form of the invention includes a base board 5 having a pair of upstanding and apertured flanges 6—6 thereon. Numeral 1 represents the hand bar, while numeral 8 and numeral 9 represent link bars. The upper end of the link bar 8 is widened as at 10 and carries the triangular-shaped plates 11 between certain corners of which the widened portion 12 of the link bar 9 is located with its pintle 13 extending through openings in the plates 11. The widened portion 10 of the link bar 8 has its pintles disposed through the openings 14 of the apertured flanges 15 located on the back of the head structure generally referred to by numeral 16. This head structure being hollow and filled with a suitable

filler 17 in which is a heating element 18 intended for the purpose of heating linoleum and other floor coverings which require heat application before installation.

5 A plate 19 is inlaid in the face side of the head 16 and has the hook-shaped rib 20 protruding outwardly therefrom for engaging the upper edge of a floor covering element.

The lower ends of the link bar 8 and hand bar 10 10 are widened as at 21 and 22, respectively, and have pintles 23 and 24, respectively, disposed through openings in the flanges 6. Brackets 25 are carried by the intermediate portion of the hand bar 7 and to these is pivotally connected the rear end of the link bar 9 as at 26.

The upper portion of the hand bar 7 is widened as at 27 to form a handle. A suitable electric cord 28 can extend from the head 16 and be equipped with a plug 29.

15 20 While the foregoing specification sets forth the invention in specific terms, it is to be understood that numerous changes in the shape, size and materials may be resorted to without departing from the spirit and scope of the invention as 25 claimed hereinafter.

Having described the invention, what is claimed as new is:

A floor covering implement comprising an elongated base plate, a pair of upstanding flanges 30 on the base plate adjacent one end thereof, a lever having a handle at one end and its opposite end pivotally connected between the flanges, a link member having one end pivotally connected between the flanges and provided with a laterally 35 disposed plate at the opposite end thereof, a second link having one end pivotally connected to an intermediate portion of the lever and its other end pivotally connected to the protruding portion of the link attached plate, a work-engaging pressure applying head, a pair of spaced flanges on the back side of the head having registering openings therein, and a pin disposed through the registering openings and through the first-mentioned link and its plate to pivotally connect the 40 45 first-mentioned link to the pressure applying head.
